SYSTEM FOR DISPENSING FLUIDS

Daniel Mapes, West Caldwell, N. J., assignor to
 Specialties Development Corporation, Bloom-
 field, N. J., a corporation of New Jersey

Application December 21, 1945, Serial No. 636,351

11 Claims. (Cl. 62—1)

1

The present invention relates to high pressure fluid medium dispensing systems, and more particularly to systems for storing and releasing a high pressure fluid medium adapted to be utilized for fire extinguishing and various other purposes.

Heretofore, fire extinguishing systems have been utilized which comprise a plurality of receptacles or containers for storing a high pressure fluid medium, such as liquefied carbon dioxide; a common manifold into which the contents of all the containers are adapted to be discharged; a discharge control means for each of the containers, including a valve member for retaining the medium in the container, a discharge outlet connected to the manifold, and fluid pressure actuated means for operating the valve member to release the medium; a fluid pressure connection between one or more containers and their respective fluid pressure actuated operating means, including a control valve; and pipes or conduits providing a fluid flow connection between the fluid pressure actuated operating means or the control valves of all of the discharge control means.

The present invention aims to improve such systems by providing a practical system wherein a single pipe or conduit serves both as a common discharge manifold and as a fluid flow connection between the fluid actuated operating means of all of the discharge control means.

An object of the present invention is to provide an improved system of the foregoing character which is simple and economical in construction, is readily assembled and is positive in operation.

Another object is to provide a single pipe system wherein the number of fluid flow connections is greatly reduced.

Another object is to eliminate the necessity of more than one common connection for the containers of the system.

Another object is to provide an improved system which lends itself to greater flexibility in the selection and arrangement of control containers adapted to be operated to effect discharge of the balance of the containers of the system.

A further object consists in the arrangement of the apparatus and the combination of devices comprising the system, whereby the foregoing objects and advantages may be accomplished.

Other and further objects of the invention will be obvious upon an understanding of the illustrative embodiment about to be described, or will be indicated in the appended claims, and various advantages not referred to herein will occur to

2

one skilled in the art upon employment of the invention in practice.

A preferred embodiment of the invention has been chosen for purposes of illustration and description, and is shown in the accompanying drawing, forming a part of the specification, wherein the single figure is a schematic view of a fluid medium storing and dispensing system illustrating an embodiment of the present invention.

Referring to the drawing, there is shown a system of the type adapted for storing and dispensing a fire extinguishing medium under pressure, such as carbon dioxide or the like. Generally described, the system comprises a bank of one or more primary or control receptacles or containers 10, and one or more secondary receptacles or containers 11, the containers illustrated herein being high pressure cylinders or the like. While two containers 10 and two containers 11 are shown by way of example, it will be understood that a system in accordance with the invention may comprise any number of containers 10 and 11, and preferably, a greater number of secondary cylinders 11 than primary or control cylinders 10.

Each of the containers 10 and 11 has connected thereto a fluid medium actuated fluid medium release control means 12 comprising retaining means, such as a main valve member 14, which controls the discharge of the fluid medium from the containers by way of an opening 15, surrounded by a valve seat 16 surrounding a main valve port, a chamber 17, and manifold means, including a conduit 18 connected to a common discharge pipe 19. The chamber 17 and conduit 18 are arranged to constitute means for conducting the fluid medium from the container to the pipe 19.

The fluid medium actuated release control means 12 further comprise main valve operating means, such as a piston 20, reciprocally movable in a cylinder 21, which is separated from the chamber 17 by a partition or wall 22. The lower portion of the cylinder 21 has a vent 23, the purpose of which is to prevent the entrapment of air. The piston 20 and the main valve member 14 are operatively connected by a piston rod 24, which passes through a gland (not shown) in an opening in the wall 22.

Associated with the means for conducting fluid from the container to the manifold are means for preventing the escape of fluid from the manifold by way of one of the fluid medium release control means 12, in the event that its container is de-

tached or is pierced by gun fire or the like. These means are illustrated herein as a check valve member, such as an aperture disc 30, located in the chamber 17 and overlying a seat surrounding the main valve opening 15. The piston rod extends through the aperture of the disc 30, and is slidably related therewith, to enable the disc to be driven upwardly from its seat when discharge of fluid through the opening 15 takes place.

The fluid medium release control means 12 of the primary containers 10 are further provided with a fluid flow connection 31 between the container and the cylinder 21 at the upper side of the piston 20, for effecting operation of the piston to unseat the main valve member 14 by means of a portion of the fluid of the container. The admission of fluid is controlled by pilot valve means 32 in the connection, and a control head 34 for operating the pilot valve means.

The control head may be of any suitable type, such as a locally manually operable head, as shown, but it will be understood that remotely operable control heads of the pneumatic, hydraulic, pull cable or electro-magnetic type could be utilized. Also, it will be understood that the control heads 34 of some or all of the primary containers may be interconnected for simultaneous operation.

The connection 31 is further provided with check valve means 35, constituted to permit the flow of fluid through the connection from the container to the cylinder 21 and to prevent the flow of fluid from the cylinder towards the container, for the purpose described hereinafter.

In order to enable fluid under pressure in the manifold, which has been released from one of the primary containers 10, to effect release of fluid from the balance of the containers in the system, means are provided for conducting fluid from the manifold to the cylinder 21. Such means, as illustrated herein, may comprise a connection 40 between the conduit 18 and the upper end of the cylinder, at a point 21 above the piston 20. It will be understood that, alternately, the connection 40 could extend from the pipe 19 to the cylinder.

The connection 40 is provided with check valve means 41, constituted to permit the flow of fluid from the conduit 18 and/or the pipe 19 to the cylinder 21, and to prevent the flow of fluid in the reverse direction.

By utilizing check valve means 35 and 41 in the foregoing described manner, the check valve means 41 is closed when fluid is admitted to the cylinder 21 by way of the connection 31, the pilot valve means 32, and the check valve means 35, thereby enabling a piston operating pressure to be established in the cylinder in a minimum period of time, and preventing the loss of such pressure by flow of the fluid into the conduit 18 and/or the pipe 19. When fluid is admitted to the cylinder 21 by way of the connection 40 and the check valve means 41, the check valve means 35 is closed, thereby enabling a piston operating pressure to be established in the cylinder, and preventing loss of fluid by way of a connection 31, in the event that a primary cylinder is removed or is impaired by gun fire or is otherwise rendered defective.

The fluid medium release control means 12 of the secondary containers 11 differ from the control means 12 of the primary containers 10, in that there is no need for a connection 31, pilot valve means 32, a control head 34, and a check valve means 35. The control means 12 for the

secondary containers 11, however, are provided with a connection 40 between the conduit 18 and the cylinder 21, to provide for operation of the piston 20 by fluid under pressure in the manifold. 5 If desired, though not essential, check valve means may be provided in the connection 40, to admit fluid to the cylinder 21 from the pipe 19, to thereby trap the fluid in the cylinder and cause the piston to be retained in main valve opening position for a period of time to insure complete discharge of the container.

In operation, the fluid of all of the containers is adapted to be discharged into the manifold by releasing the fluid of one or more of the primary containers. 15 For example, by operating the control head 34 to unseat the pilot valve 32 of the primary cylinder 10 at the extreme left in the bank, fluid from the container flows through the connection 31 and into the cylinder 21, causing the piston 20 to be actuated to effect unseating of the main valve member 14. The fluid in the cylinder is prevented from flowing to the manifold by the check valve means 41. When the main valve member is unseated, fluid passes 20 through the main valve opening, and the check valve disc 30 is moved upwardly and away from the opening 15, whereby the fluid flows into the manifold by way of the conduit 18.

Thus, when the contents of the primary cylinder are discharged into the manifold, a portion 30 of the fluid is directed to the valve actuating cylinders 21 of the other primary cylinder and each of the secondary cylinders by way of the conduits 18, the connections 40 and the check valve means 41. The fluid in the cylinders effects 35 operation of the pistons, whereby the valve members are unseated, and the contents of the containers are discharged into the manifold.

It will be noted that upon discharge of each 40 of the containers, a portion of the fluid is adapted to be directed from the container to its cylinder 21 to supplement the pressure fluid initially supplied by way of a pilot valve or the manifold, thus 45 insuring full stroke operation of the piston and complete unseating of the main valve member 14, whereby rapid discharge of the containers is effected.

From the foregoing description it will be seen 50 that the present invention provides an improved system for discharging a fire extinguishing medium or the like. The system is simple in construction and can be readily assembled by reason of the fact that there are a minimum number of connections. The invention further provides 55 a one pipe system which is positive in operation and has a high discharge rate, thereby rendering it particularly adapted for fire extinguishing purposes and the like.

As various changes may be made in the form, 60 construction and arrangement of the parts herein, without departing from the spirit and scope of the invention and without sacrificing any of its advantages, it is to be understood that all matter herein is to be interpreted as illustrative and not in any limiting sense.

It is also to be understood that the following 65 claims are intended to cover all the generic and specific features of the invention herein described, and all statements of the scope of the invention which, as a matter of language, might be said to fall therebetween.

I claim:

1. In combination, a plurality of receptacles for containing a fluid under pressure, means for each 75 of said receptacles for normally retaining the

pilot valve in said connection for controlling the flow of fluid from said receptacle to its operating means, and means in said connection for preventing the flow of fluid from said operating means towards said receptacle.

9. In combination, a plurality of receptacles for containing a fluid under pressure; a main valve, including a main valve member and a main valve port, for each of said receptacles for normally retaining the fluid therein and operable to release the fluid therefrom; a manifold into which the fluid may be delivered from all of said receptacles; means for conducting the fluid from each of said main valves to said manifold; a check valve in each of said conducting means for substantially preventing the flow of fluid from said manifold through said main valve ports of receptacles which have been removed or emptied at a time the main valves of such receptacles have to operate to normally release the fluid therefrom; fluid actuated operating means for each of said main valves, including a cylinder, a piston and a piston rod adapted to unseat said main valve member; means for conducting fluid from said manifold to each of said cylinders; a check valve in each of said last conducting means for preventing the flow of fluid from said cylinders to said manifold; a fluid flow connection between at least one of said receptacles and its cylinder; a pilot valve in said connection for controlling the flow of fluid from said receptacle to its cylinder; and a check valve in said connection for preventing the flow of fluid from said cylinder towards said receptacle.

10. In combination, a plurality of receptacles for containing a fluid under pressure, valve means for each of said receptacles for normally retaining the fluid therein and operable to release the fluid therefrom, delivery means into which the fluid may be delivered from all of said receptacles,

5 fluid actuated operating means for said valve means of each receptacle, means for conducting fluid from said delivery means to said operating means, and check valve means in said conducting means for preventing the flow of fluid from said operating means to said delivery means.

11. In combination, a primary receptacle for containing a fluid under pressure, a secondary receptacle containing a fluid under pressure, delivery means into which the fluid from said primary and said secondary receptacle may be delivered when it is released, primary fluid retaining means for normally retaining the fluid in said primary receptacle and operable to release the fluid therefrom, primary fluid actuated operating means for said primary retaining means to release the fluid retained thereby, a direct fluid flow connection between said primary operating means and said primary receptacle, primary pilot 10 valve means for said fluid flow connection, actuating means for said primary pilot valve means, fluid actuated fluid release control means including retaining means for said secondary receptacle for normally retaining the fluid in said secondary receptacle and operable to release the fluid therefrom, and a fluid flow connection between said delivery means and said fluid actuated fluid release control means for said secondary receptacle.
